HARMONIC OSCILLATION GENERATING
SYSTEMJean L. Delvaux, Asnières, France, assignor to
General Electric Company, a corporation of
New YorkApplication February 19, 1948, Serial No. 9,363
In France October 16, 1945Section 1, Public Law 690, August 8, 1946
Patent expires October 16, 1965

4 Claims. (Cl. 250—36)

1

My invention relates to an oscillation generating system of the type in which one or more harmonically-related frequencies are derived from a fundamental frequency.

Circuits embodying my invention are particularly adapted to use a duplex electron discharge device of known triode-hexode type, or similar type. Such a tube comprises within a common envelope a triode section and a multi-grid section which may be of the pentode, hexode, heptode, type etc., having at least two grid electrodes each capable of acting independently on the electron stream in the multi-grid section. In a conventional circuit utilizing a triode-hexode, for example, the triode section is commonly included in an oscillator circuit and the hexode section is included in a modulator and mixer circuit. The control grid of the triode section is, in general, connected directly through a lead, which may be either internal or external, to one of the control grids of the multi-grid section. Thus, oscillations impressed on the triode section are supplied directly to this grid of the multi-grid section. For convenience, this grid may hereafter be termed the modulation grid. In accordance with usual practice, signals which are to be heterodyned with those produced in the triode oscillator section are impressed on another control grid in a multi-grid section, which may hereafter conveniently be termed the signal grid.

In accordance with the principles of the present invention, means are provided for deriving from a triode oscillator circuit a harmonic voltage whose frequency is an integral multiple of the fundamental oscillator frequency. This harmonic frequency is then applied to the signal grid of the multi-grid section where it beats against the fundamental frequency supplied directly to the modulation grid. Finally, there may be selected in the output circuit of the multi-grid section one or more harmonic frequencies equal to the sum or difference frequency, and also the fundamental frequency if desired.

It is a principal object of the invention to provide an improved oscillation generating system for deriving from a primary source of oscillation frequency f one or more harmonically-related frequencies of the form $(n \pm 1)f$, where n is an integer.

It is another object of the invention to provide an improved oscillation generating system in which a plurality of harmonically-related frequencies may be generated and supplied from

2

relatively simple circuits associated with a single electron discharge device of the duplex type.

It is more specifically an object of the present invention to provide a simple and inexpensive oscillation generating system capable of providing a fundamental frequency f and a plurality of harmonically-related frequencies of the form $(2n \pm 1)f$, where n is an integer, this system comprising circuits associated with only a single tube of the triode-hexode type, or similar type.

For additional objects and advantages, and for a better understanding of the invention, attention is now directed to the following description and accompanying drawings, and also to the appended claims in which the features of the invention believed to be novel are particularly pointed out.

In the drawings:

20 Fig. 1 is a circuit diagram of one form of oscillation generating system embodying the invention; and

Figs. 2 and 3 are circuit diagrams of modified embodiments of the invention.

25 Corresponding elements in the several figures of the drawing have been designated by corresponding reference numerals.

Referring now particularly to Fig. 1, there is represented a system employing a known form of duplex tube 10 having a left-hand triode section 10a and a right-hand hexode section 10b. The electron streams in the two sections are electrically independent, and it will be understood that separate tubes might be utilized, although the construction illustrated is generally preferable for reasons of convenience, cost and physical size.

30 The triode section 10a comprises a cathode 11, control grid 12 and anode 13. These are connected in a suitable oscillation generating circuit. As represented, this circuit comprises a piezo-electric crystal element 14 connected between anode 13 and grid 12 and a resistor 15 connected between grid 12 and cathode 11.

40 Anode operating potential is supplied from any suitable B+ source, represented conventionally by battery 16 through conductor 17, a resonant circuit 18 and a resistor 19. The cathodes of both sections of device 10 are returned to the grounded negative terminal of the supply source 16 through a conventional resistance-capacitance network 20 which serves to provide an operating bias for certain electrodes of section 10b. In accordance with known practice, the crystal 14

45 may be shunted by a capacitor 23, the resistor 50

55

15 may be shunted by a capacitor 24, and both these elements in series may be shunted by a capacitor 25.

Assume now that the elements of the oscillator circuit just described are properly adjusted so as to cause the crystal 14 to oscillate at a certain fundamental frequency f . The resonant circuit 18 is then tuned to a harmonic frequency nf , where n is any integer. Preferably, the circuit 18 is tuned to an even harmonic frequency, which may be represented as $2nf$, because the even harmonics in the anode circuit of the oscillator section will in general be more intensive than the odd harmonics.

The multi-grid section 10b of $2n$ comprises a cathode 30, a plurality of grids 31—34, and an anode 35. The first or signal grid 31 is arranged to have harmonic frequency voltage impressed thereon by means of a winding 36 coupled to the resonant circuit 18. The third or modulation grid 33 has oscillations of the fundamental oscillator frequency impressed thereon by reason of the direct internal connection 37 between grid 33 and the triode grid 12. Suitable operating essentials are impressed upon the second and fourth grids 32 and 34 in conventional manner from supply source 16 through a filter network comprising a resistor 38 and by-pass capacitor 43. Anode 35 is also connected to the positive terminal of supply source 16 through a pair of resonant circuits 39 and 40 in series and conductor 47.

Assuming that a fundamental frequency f is impressed on modulation grid 33 and an even harmonic frequency $2nf$ is impressed upon signal grid 31, the circuits 39 and 40 may be tuned to select the sum and difference frequencies $(2n+1)f$ and $(2n-1)f$, respectively. These two frequencies may be supplied to suitable output circuits (not shown) by means of the coils 41 and 42 coupled to the resonant circuits 39 and 40, respectively.

The amplitudes of the harmonic frequencies supplied to the output circuit may be adjusted by adjusting the impedance of the self-bias network 28 in a cathode return circuit of section 10b. It will of course be apparent that the frequencies may also be stabilized in conventional manner by thermostatic control of the temperature of crystal 14, and if necessary by thermostatic control of the other frequency-determining elements of the system.

Fig. 2 represents a modified embodiment of the invention which operates in substantially the same manner as that of Fig. 1 but which differs in that the tuned circuit 18 is connected in shunt to the anode circuit of section 10a through a coupling capacitor 50, instead of being connected in series with the anode supply circuit as in the case of Fig. 1.

It will also be apparent that other forms of oscillator circuits known to the art may be employed. In some cases it may be desirable to supply oscillations of the fundamental frequency f to the control grid 12 from an external oscillation generator. A circuit arrangement of this latter type is represented in Fig. 3. This circuit differs from that of Fig. 2 in that the fundamental frequency oscillations are supplied from any suitable external source 54 and impressed upon control grid 12 through a coupling capacitor 52.

While certain specific embodiments have been shown and described, it will, of course, be understood that various other modifications may be

made without departing from the invention. The appended claims are therefore intended to cover any such modifications within the true spirit and scope of the invention.

5 What I claim as new and desire to secure by Letters Patent of the United States is:

1. An oscillation generating system comprising a first electron discharge path including an anode, cathode and control grid, means for impressing oscillations of fundamental frequency f on said control grid, a resonant circuit connected between said anode and cathode tuned to a harmonic frequency nf , where n is an integer, a second electron discharge path includ-

15 ing an anode, cathode and a plurality of grid electrodes, means comprising a direct connection from said control grid to one of said grid electrodes for impressing frequency f thereon, means coupling said resonant circuit to another 20 of said grid electrodes to impress frequency nf thereon, and an output circuit connected between the anode and cathode of said second device tuned to select a beat frequency from the group consisting of $(n+1)f$ and $(n-1)f$.

25 2. An oscillation generating system comprising a first electron discharge path including an anode, cathode and control grid, an oscillator circuit including said path and operating at a fundamental frequency f , a resonant circuit connected between said anode and cathode tuned to an even harmonic frequency $2nf$, where n is an integer, a second electron discharge path includ-

30 ing an anode, cathode and a plurality of grid electrodes, means comprising a direct connection from said control grid to one of said grid electrodes for impressing frequency f thereon from said oscillator circuit, means coupling said resonant circuit to another of said grid electrodes to impress frequency $2nf$ thereon, and 35 an output circuit connected between the anode and cathode of said second device tuned to select a beat frequency from the group consisting of $(n+1)f$ and $(n-1)f$.

40 3. An oscillation generating system comprising a duplex electron discharge device having a triode section and a multi-grid section within a common tube envelope, a direct connection from the grid of said triode section to one grid of said multi-grid section, an oscillator circuit including said triode section and operating at a fundamental frequency f , a resonant circuit excited by said oscillator circuit and tuned to an even harmonic frequency $2nf$, where n is an integer, means for impressing said harmonic frequency on another grid of said multi-grid section, and an output circuit including said multi-grid section and comprising a tuned circuit resonant at a beat frequency from the group consisting of $(n+1)f$ and $(n-1)f$.

45 4. An oscillation generating system comprising a duplex electron discharge device having triode and multi-grid sections within a common tube envelope, said multi-grid section including a modulation grid and a signal grid, a direct connection between the grid of said triode section and said modulation grid, an oscillator circuit including said triode section and operating to impress a fundamental frequency f on said directly-connected grids, a resonant circuit excited by said oscillator circuit and tuned to an even harmonic frequency $2nf$, where n is an integer, means for impressing said harmonic frequency on said signal grid, and an anode output circuit for said multi-grid section including

50 two resonant circuits, one tuned to select the

difference frequency $(2n-1)f$ and the other tuned to select the sum frequency $(2n+1)f$.
